UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed June 29, 1918. Serial No. 242,523.

To all whom it may concern:

Be it known that I, WILLIAM L. MCGRATH, a citizen of the United States, residing at Elmira, in the county of Chemung and State of New York, have invented certain new and useful Improvements in Engine Starters, of which the following is a specification.

My invention relates to a starter for engines, more particularly internal combustion engines, and pertains to the drive or transmission portion thereof between the starting motor and the part, such as the fly wheel, of the engine to be started.

15 The object of my invention is to provide simple and efficient and improved means in such a drive for transmitting power therethrough initially with a yielding pressure and finally with a rigid or positive pressure.

20 In drives of the class and character to which my invention is particularly applicable a yielding driving connection in the form of a coiled spring is provided to transmit the power yieldingly and also to store up energy until the fly wheel is broken loose and started. Such a spring has its limits and in order to prevent any overtaxing of the spring and to provide a positive or rigid drive when the tension limit of the spring is 25 reached and to thereby prevent setting of the spring, my present invention is employed.

My invention consists in providing a simple and efficient structure which is capable of accomplishing the above recited results and which is compact and within the lines or dimensions of the standard Eclipse-Bendix drive so as to be interchangeable therewith in the mountings for such 35 drive. My improved structure also provides means for accommodating or cushioning the back lash of the spring occurring when the same unwinds, and also means for effectually securing the driving head or collar to the driving shaft which may be the armature shaft extended or a countershaft accordingly as the drive is of the so-called single reduction type or the double reduction type.

50 In the drawings Fig. 1 is an elevation partly in section, of a drive embodying my invention; Fig. 2 an end elevation as indicated by the line 2² of Fig. 1; Fig. 3 a plan view of a portion of the drive showing parts thereof in section; Figs. 4 and 5 sec-

tions on the correspondingly indicated section lines of Fig. 1; and Figs. 6 and 7 perspective of the two parts forming the rigid driving connection for the screw shaft.

For convenience in illustration and description of my invention I have shown a specific embodiment thereof in the type of drive known as the Eclipse-Bendix drive, but it will be understood that my invention is not to be limited to this particular type but may be embodied in types of other construction. Moreover, while I have shown my invention in a structure of the single reduction type, it will be understood that it is equally applicable to a structure of the double reduction type.

Referring to the particular embodiment shown, the power motor such as an electric starting motor is indicated at A. In the structure shown the armature shaft is extended to form a driving shaft 1 on which the drive or transmission is mounted and by which it is driven. To the outer end of this shaft there is secured by means of the stud 2 a driving head in the form of a somewhat extended collar or sleeve 3 through which said stud passes and thence into the driving shaft with its plain cylindrical end 2^a, entering a location hole 3^a in such shaft. This sleeve has an inwardly projecting extension or lug 4 which by preference is somewhat less than a semi-circle and which constitutes one of two substantially similar jaws of a clutch, for the rigid driving connection between such sleeve and the screw shaft.

As shown and by preference, the driving head or sleeve 3 is secured to the driving shaft 1 mainly by a plurality of Woodruff keys 5 and also by the projecting end 2^a of the stud. The sleeve is of such length that I am enabled to thus employ the two keys and at the same time locate them towards the inward portion of the sleeve and away from the plane of the hole 3^a, so that the full strength of the shaft is maintained.

The screw shaft 6 is here in the form of a sleeve or hollow shaft mounted upon the driving shaft 1 and operatively connected at all times with the driving head 3 with an operatively yielding connection and at one time in the operation of the drive adapted to be operatively connected in a positive or rigid manner. This yielding driving con-

nection consists of a coiled spring 7, one end of which is anchored to the stud 2 and the other to a stud 8 which screws into the driving head portion 6^a of the screw shaft. As shown such portion is integral with the screw shaft but this is not essential, as it may be made separate and detachable and be secured thereto.

The said rigid driving connection consists of a clutch one member of which is the lug 4 already described and the other a corresponding lug 9 extending outwardly from and forming a part of the driving head 6^a of the screw shaft. In the normal position 15 of the parts as shown in Fig. 1 these clutch jaws are not in contact but there is a clearance or cushioning space 10 provided between two adjacent edges of such clutch jaws, the purpose of which space will be 20 made apparent during the description of operation.

Upon the screw shaft is mounted the driving member adapted to cooperate with a rotatable part of the engine to be started. This 25 member is in the form of a pinion 11, screw threaded on the screw shaft and adapted to mesh with such rotatable part, as for instance with the teeth 12^a of the fly wheel 12.

Describing the operation of the drive and 30 starting with the parts in the normal position shown in Fig. 1, the motor is now started, whereupon the driving shaft 1 is rotated. The power is transmitted from this shaft to the screw shaft through the driving spring 35 7, whereupon such screw shaft will be rotated and the pinion 11 will be automatically meshed with the fly wheel. After such meshing the pinion will partake of the rotary movement of the screw shaft and the power 40 will be transmitted initially through the driving spring which will be partially wound, and such action will continue until this relative movement of the driving head or sleeve 3 brings two of the edges of the 45 clutch jaws together into contact whereupon the torque above that necessary to wind the spring to this point will thereafter be transmitted in a positive and rigid manner through said clutch. In practice the clutch 50 jaws 4 and 9 are so made and related to each other that said rigid connection will occur at a predetermined point below the elastic limit of the spring, thereby preventing destruction or breakage of the spring but without 55 interfering with the flexibility of such spring acting within safe limits. Thus the angular deflection of the driving parts is cushioned by the spring and the same become rigidly connected at the proper time, there- 60 by relieving the spring. The described form of jaws allows the maximum torsional or angular movement with the maximum strength of jaw.

After the engine is started on its own 65 power, the pinion 11 is automatically de-

meshed and returned to normal position. When the driving action through the shaft 1 is relieved and the pinion is demeshed the tension of the coiled spring will restore the parts to normal position and owing to the rapidity of this unwinding movement of the spring, the driving head or sleeve 3 is liable to be rotated backwardly beyond the normal point relative to the screw shaft. Were the two jaws of the clutch in contact during the 75 normal position, this back lash or rebound of the spring would be liable to cause the jaw 4 to strike the other jaw with considerable force and jar. To avoid such action I provide the clearance or cushioning space 80 10 so that the excess rotation of the sleeve on such rebound of spring will be accommodated by such space and the other jaw will not be struck thereby.

Thus, according to this construction, the 85 driving and driven elements are limited in their relative movements in both directions in order to relieve the spring of excess torsion action and also of rebound action.

The clutch jaws 4 and 9 are so constructed 90 and arranged that a longitudinal yielding movement of the screw shaft is permitted against the compressing action of the spring, in the event that the pinion teeth and fly wheel teeth should abut end to end. The 95 driven element thus has a longitudinal movement which is independent of its rotary movement in both time and extent. Moreover, the construction is such, as to the sleeve 3 and the driven head 6^a, that there is no 100 possibility of the spring wrapping down and becoming wedged between these two parts even in case the elastic limit should be reached or exceeded before the clutch jaws 105 engage each other.

The advantages of the driving head construction are that it increases the strength of the driving shaft particularly by permitting the use of a plurality of small keys, together with a shallow hole and not a through hole in the shaft, and also eliminates the necessity of a spring barrel to prevent wedging of the spring when wrapping down. Moreover, the stud 2 serves to also 110 fix the position of the drive assembly longitudinally and takes the longitudinal thrust of the screw shaft when the pinion teeth and the fly wheel teeth abut end to end.

As shown in Fig. 1, I provide special 115 means for anchoring the free ends or eyes of the coiled spring to the driving heads 3 and 6^a respectively. As shown, the extreme end of each eye is bent or swaged outwardly as at 7^a so as to enter a recess 6^b in the head of the screw shaft and a recess 3^b in the driving head 3, whereby these eyes are securely anchored in place when the studs 2 and 8 are screwed down tight. In addition I employ locking washers 13 for preventing rotation and loosening of these 120

studs. The lower edges of these eyes are outwardly bent and swaged as at 7^b in order to enter the depression 6^c of the head of the screw shaft and a depression 3^e in the driving head 3, respectively. Thus the eyes are interlocked securely on opposite sides when the studs are screwed in place and are prevented from any slight rotation or twisting.

10 I claim:

1. A drive for engine starters including a rotatable driving element and a rotatable driven element having on their adjacent ends corresponding clutch members adapted to operatively engage each other by permitting longitudinal movement of such elements which movement is independent of their rotary movement, and a coiled spring connected at its ends to said elements respectively, said elements having a limited relative rotary movement, one with respect to the other and the clutch members being normally separated longitudinally to permit of a yielding pressure and separated angularly to provide a cushioning space between them.

2. A drive for engine starters including a rotatable driving element and a rotatable driven element, said elements having cooperating clutch jaws which are permitted limited relative movement one with respect to the other both in a rotarial direction and in a longitudinal direction, and adapted to operatively engage each other for direct driving when one element is partially rotated in one direction relative to the other element, and a coiled spring connected at its opposite ends to the two elements respectively, said jaws being normally separated longitudinally to permit of a yielding pressure and separated angularly to provide a cushioning space between them, and said spring being arranged to resist said angular and longitudinal movements of said elements.

3. A drive for engine starters including

a rotatable driving element and a rotatable driven element having on their adjacent ends coating clutch members and having a longitudinal movement one toward the other to permit of a yielding pressure, and a coiled spring connected at its ends to said elements respectively, said elements having a relative rotary movement and said clutch members being normally separated angularly to provide a cushioning space between them, the longitudinal movement of said driven element being independent of its rotary movement in time and extent.

4. An engine starter for transmitting power initially with a yielding pressure and finally with a rigid pressure comprising a rotatable driving element having a driving clutch member thereon, a rotatable driven element having a longitudinal movement which is independent of its rotary movement, a driven clutch member on said driven element separated longitudinally and angularly from said driving clutch member and adapted to coast therewith, and a coiled spring connected at its opposite ends to the two elements.

5. Starting mechanism comprising a drive shaft, a driven shaft, a source of power connected to said drive shaft, connecting means between said shafts adapted to build up the torque on the driven shaft, and means for positively connecting said shafts when the torque has been built up to a predetermined degree.

6. Starting mechanism comprising a clutch member, a drive shaft operatively connected thereto, a second clutch member adapted to be yieldingly engaged by said first clutch member, a driven shaft connected to said second clutch member, and means dependent upon the torque built up in the driven shaft for positively connecting said first clutch member to said driven shaft.

WILLIAM L. McGRATH.
